UNITED STATES PATENT OFFICE.

FREDERICK FERRIS, OF LONDON, ENGLAND; ASSIGNEE TO PETER PAN GRAMOPHONE COMPANY, LIMITED, OF LONDON, ENGLAND; APPLICANT FOR A PATENT IN THE UNITED STATES OF AMERICA, IN THE NAME OF FREDERICK FERRIS, OF LONDON, ENGLAND, FOR A GRAMOPHONE.

Application filed January 2, 1923, Serial No. 610,344, and in Great Britain January 20, 1922.

This invention provides an improved gramophone of extremely light and portable construction, with its main parts collapsible and detachable, so that the gramophone may be closed up in a compact manner:

According to the invention, the gramophone is provided with a collapsible record table, as one of its chief features, which table can be folded into small compass for housing in the closed-up box when detached and not in use; similarly there is employed a collapsible horn. The sound-box is constructed to be movably and removably mounted on a light detachable support, and the case or box containing the motor, and its lid, are formed with recesses and means to accommodate snugly all the detachable and collapsible parts in a compact manner as will appear later.

In order that the said invention may be readily understood reference is to be had to the following description and accompanying sheets of drawings, wherein:—

Figure 1 is a part-sectional elevation of one embodiment of the invention, showing the case open, and parts attached ready for use.

Figure 2 is a plan view thereof.

Figure 3 is a view similar to Figure 2 but with parts detached, collapsed and packed together in readiness for closing the case.

Figure 4 is a fragmentary view of a detail hereinafter referred to.

Like letters of reference indicate corresponding parts in the several views.

Referring to the drawings, the box *a* houses any suitable type of motor, a part of which is shown in Figure 1. Across the top of the motor is formed a platform *b* which is disposed below the level of the top edge of the box or casing *a* so as to leave a space in which to pack various members, as is described later. The lid *c* of the box is also a recessed member in order to fit over articles packed away above the platform *b*, and projecting above the top of the case *a*; said lid has a spring clip *d* to receive the motor handle *e* when not in use.

The sound-box *f* is supported and carried turnably on a light detachable support *g* carried over the top of the platform *b*. In order that the sound-box can travel across the record as the latter revolves, it may be slidable on the support, or the support itself movable; an example of the latter arrange-

ment is depicted in the drawings. Here the support *g* has a right-angular bend at each end, the arms so formed being in planes at right angles to each other, one being vertical and adapted to pivotally fit a socket *i*, secured to the lid *c*, and one lying horizontally so that its end *j* can swing as indicated by the dotted line—Figure 2. This end *j* is adapted to pass into a guide sleeve *k* formed on the sound-box *f*, so that the latter can be swung over into the position illustrated in Figures 1 and 2 when the needle is to be engaged with the record. A small sprung pressed pin *l*—see particularly Figure 4—engages an annular groove in the end of the support arm to ensure a firm fit.

The sound-box *f* is formed with a tone-arm to which the horn is fitted. The phrase tone-arm is used to indicate any connecting medium between the sound-box proper and the horn, and in Figure 2 will be seen a cylindrical flange *m* of the usual kind formed on a sound-box which is employed to function as a tone-arm, and to which the smallest section of the collapsible horn *n* is frictionally fitted. The horn *n* consists of a plurality of frusto-conical sections of descending sizes assembled one within the other so that they may be collapsed together to collectively occupy the height of one, as in Figure 3, or extended, fitting together frictionally, to constitute a complete horn as in Figures 1 and 2.

The record table consists of a boss *o* (which may be any convenient shape) to which collapsible arms or spokes *p* are secured; the arms are radially disposed and may be hinged at *q* as shown, and are constructed in any suitable manner to afford a protective grip on records when laid thereon and for this purpose may be covered or padded with rubber, baize or the like, as at *r*; the spokes *p* may be arc-shaped or otherwise formed to give a larger gripping surface. The boss *o* fits over the driving spindle of any ordinary motor, but for sake of space economy, I may arrange the speed regulator *s* so that movement is possible after the "slow" position is obtained to afford a stronger and effective frictional engagement with the usual slidable disc *t* of the governor, and thus constitute also a positive brake and stopping appliance; *s'* is the actuating knob of this regulator. If desired, however, such as when an independent speed control is de-

sired for setting to a requisite speed for a number of records, a separate brake may be used as ordinarily. In the example illustrated *u* is the brake knob which presses on a springy leaf *u* to brake the the disc *t*.

The platform *b* of the box *a* has a circular recess *v* into which fits the horn *n* when collapsed, and a side recess *w* with an orifice at one end leading down into the box and a branch *x* at the other end to accommodate the double-bend shape hereinbefore described, of the sound-box support *g*. The branch recess *x* also takes the boss *o* of the collapsible platform—as seen in Figure 3—the legs of which can lie along the platform *b*, resting against the stop-plate *y*. A further recess *z* is formed in the platform *b* to receive projecting parts of the sound-box in order that same may lie flatly on the platform.

In the drawings, *a'* indicates a box catch whereby when the parts are grouped as shown in Figure 3, the lid may be closed and fastened to make the compact, light, and portable appliance aimed at.

The handle *e* may be foldable or otherwise collapsible, and as an auxiliary feature, there may be provided a butterfly key *h* for winding the motor when the record is on the table, and it is impossible to use the cranked handle *e*. This key *h* is shown stored away in a circular orifice in the platform *b*.

I claim:

1. A record table adapted for use in connection with talking machine casings of less dimension than the diameter of the table, comprising a boss having a plurality of radial extensions, and a plurality of radially arranged arms each of which has a hinged connection with an extension of the boss.

2. A collapsible record supporting table adapted for use in portable talking machines comprising a member having a spindle receiving opening, and a plurality of record supporting arms pivotally connected with said member.

In testimony whereof I have affixed my signature hereto this 22nd day of December 1922.

FREDERICK FERRIS.
